UNITED STATES PATENT OFFICE

2,662,496

THREAD HANDLING MECHANISM

Mathias Pedersen, Valley Stream, N. Y., assignor to American Machine & Foundry Company, a corporation of New Jersey

Original application April 10, 1948, Serial No. 20,198, now Patent No. 2,604,863, dated July 29, 1952. Divided and this application December 20, 1951, Serial No. 262,518

11 Claims. (Cl. 112—171)

1

This invention relates to sewing machines, and more particularly to sewing machines capable of making special types of stitches either for decorative or utilitarian purposes, especially the type in which a double pointed needle, provided with a thread having a loose and a fixed end, is projected back and forth through the work fed either manually or automatically over a work supporting table into the range of action of the needle.

This invention consists further in improvements in sewing machines of the type illustrated in Johnson Patents 2,368,066; 2,386,800 and 2,389,-151, and particularly to improvements in mechanisms for decorating coats of all types, men's and women's suits and other garments where this type of decoration is desired. This application is a division of applicant's copending application, Serial Number 20,198, filed April 10, 1948, for Special Stitch Sewing Machine, now Patent 2,604,863, granted July 29, 1952.

The present invention consists of novel mechanism for handling the thread and preventing it from being spitted or broken by the needle, or the thread puller which pulls the loose end of the thread through the work during the formation of each stitch.

The invention is characterized by the provision of an improved thread trap and a thread support which are mounted beneath the work support table in relatively close proximity to the needle, and means for displacing of thread out of the path of the needle into a thread trap and onto the thread support, so that due to the operation of the thread puller which pulls the loose end of the thread through the work, the danger of breakage of thread is greatly minimized and substantially eliminated.

With these and other objects in view but not specifically mentioned, the invention consists in the novel method, and certain combinations and constructions which will be hereinafter fully described, and then set forth in the claims appended.

In the accompanying drawings which form a part of this specification and in which like characters of reference indicate the same or like parts:

Fig. 1 is an end elevation of the novel thread guide and trap mechanism;

Fig. 2 is an isometric view showing the lower needle bar and thread guiding mechanism in action, and

Fig. 3 is a side elevation of the mechanism constituting the invention.

2

Referring to the drawings, the mechanism constituting the present invention is adapted primarily for use in the machine shown in the above referred to Johnson patents, although it may have use in other sewing machines capable of utilizing structure made in accordance with the invention. In the illustrated embodiment, it is shown in conjunction with a machine for making "angle stitches," as described hereinafter. In Figure 3 it will be seen that there has been provided upper and lower needle bars 98, 100 respectively, which project a double pointed needle N, having an eye located between the points, back and forth through material or work to be sewed and form therein a plurality of under and over type stitches. The eye of the needle is threaded with a thread which after the first stitch is made, has a fixed and a loose end. During the sewing operations and after the formation of each stitch, the loose end of the thread is pulled through the work in known manner. The mechanism for operating the needle bars, thread puller and other thread handling means in general can be of the same type as that described in the above referred to Johnson patents.

As is well understood in the art, double pointed needle N is grasped alternately by chucks 102 in needle bars 98 and 100, and projected back and forth with the thread through the work. Needle bars 98, 100 are mounted in brackets 99 connected to cam actuated levers (not shown) which reciprocate them in proper timed relation with the operation of the stitch forming mechanism 56 and other moving parts of the machine in order to form the desired types of stitches. Reference is made to Johnson Patent 2,368,066 which shows in detail suitable mechanism for operating the needle bars and coacting means for pulling the loose end of the thread through the work.

In order to advance work (not shown) over work supporting table 4, and position it properly thereon with respect to needle N, a presser foot 127 is provided. This foot carries a toe 131 mounted on pivot pin 133 in foot 127. A spring urged plunger (not shown) in a vertical bore (not shown) in foot 127 normally urges toe 131 downwardly to substantially horizontal position such as shown in Figure 3. The upward movement of toe 131 is limited by a stop 141 mounted on foot 127. Toe 131 is provided with two elongated portions 139 spaced apart a distance greater than the diameter of the needle. Elongated portions 139 overlie a portion of angle work shifting and lifting plate 52 over which the work is moved. The construction and operation of plate 52 are

fully shown and described in said copending application, and therefore further detailed showing and description, except what is necessary to make the operation of the mechanism constituting the present invention clear, are omitted in the interest of brevity.

Presser foot 127 cooperates with an upper feeding foot 121 and a lower feed plate 123 provided with a conventional toothed work feeding dog 122. Plate 52 is provided with a cutout (not shown) which allows upper work feeding foot 121 and feeding dog 122 to coast, engage work to be fed while located upon plate 52 and travel it forwardly beneath raised needle N. The construction and operation of work feeding foot 121 and the operation of the presser foot 127, except as mentioned above, can be substantially the same as that shown in Johnson Patent 2,389,151.

The operation of plate 52 with respect to work (not shown) is such that, every time needle N is passed upwardly through the work, the portion of the work to be stitched is inclined at an acute angle with the path of travel of the needle therethrough. Preferably the work is positioned in a plane substantially parallel with the axis of the needle. This arrangement makes it possible to dispose the major portion of the thread forming each angle stitch in the work.

When needle N is held by upper needle bar 98, plate 52 is returned to its inoperative or substantially horizontal position relative to work support table 4. Feed foot 121 and feed bar 122 are then operated to advance the work beneath upraised needle N, and when needle bar 98 again moves downwardly, needle N is passed through substantially horizontally positioned work, completing the stitch.

It is important to maintain the thread out of the path of movement of the needle beneath table 4 and prevent splitting of the thread by the needle, or twisting of the thread thereabout as needle N moves upwardly towards the work, which would cause loss of time due to thread breakage. In order to overcome this difficulty, the improved thread guiding and handling mechanisms constituting the invention are provided.

As shown in Figures 1, 2 and 3, operating in conjunction with the stitch forming mechanism described hereinabove, and functioning to control the thread while the loose end L is being pulled through the work (not shown) by thread puller 203, is an improved thread guide and trap device designated generally 210. This device consists of a thread guide, which may be a rod 272, suitably attached to and projecting outwardly from member 271 secured to the machine frame 2. Thread guide and trap device 210 is positioned above the thread supporting drum 209. Thread puller 203 and the thread supporting drum, indicated in Figure 3, are of the same construction and operate in the same manner as shown in Johnson Patent 2,368,066. Rod 272 is formed with a substantially horizontal part 273 and a downwardly inclined part 274.

Mounted on member 271 above guide rod 272 is a co-operating trap forming and guide such as rod 276. Rod 276 is provided with a substantially horizontal portion 277, a substantially vertical part 278, a portion 279 parallel to part 273 of rod 272, and a turned up nose portion 280.

Secured at 282 to frame 2 beneath table 4 is a thread lint trap and guide 284 provided with a vertical flange 286 and a substantially horizontal thread support or plate section 288 which catches lint dropping from the work and thread

as the result of needle N moving with the thread through the work and also supports slack thread clear of the path of movement of needle N. Plate section 288 has a cut out portion 289 which allows lower needle bar 100 to move up and down beneath table 4. It is also provided with an upstanding projection 290 which tends to hold lint on plate section 288, and a tapered thread guide 292.

During the operation of thread puller 203 about drum 209 shown in dotted lines in Figure 3, in pulling the loose end L of thread T through work (not shown), the thread is initially disposed as at I in Figure 2. However, when needle N is moved upwardly, this end of the thread is displaced laterally rearward to the position indicated at II wherein it is guided up the inclined face of guide 292 into the space between the rear face of guide 292 and flange 286. At the same time the thread is moved between rods 272 and 279 and upwardly into the space between rod portion 278 and frame 2, where it is held by finger 294 on thread shifting or displacing member 296. While so held, the loose end of the thread is clear of the path of movement of needle N. When thread puller 203 has completed its thread pulling operation in which the loose end L of the thread is disposed on the thread receiving drum 209, displacing member 296 moves from the position shown in broken lines in Figure 1 to that shown in full lines.

Thread displacer 296 is pivotally mounted on a pin 298 in lever 300 fulcrumed at 302 on an extension of frame 2. The other end of thread displacer 296 is pivotally connected to lever 304 swingably mounted on a stud 306 supported by a bracket 308 suitably mounted on the frame of the machine. A cam follower 310 on lever 304 runs in a cam track in drum cam 312 on shaft 205 so designed that displacer 296 is so operated that finger 294 engages the thread at the proper time in order to function in the manner described.

The invention above described may be varied in construction within the scope of the claims, for the particular device, selected to illustrate the invention, is but one of many possible concrete embodiments of the same. It is not, therefore, to be restricted to the precise details of the structure shown and described.

I claim:

1. In a sewing machine of the type having a work support table, an upper needle bar and a lower needle bar adapted to pass a double pointed needle and a thread back and forth through work to be stitched, a thread receiving drum and a thread puller for pulling the loose end of said thread through said work and disposing it upon said drum; a thread support having a relatively wide, substantially flat thread supporting surface, a lint trap, means mounting said support and trap above said drum and adjacent said lower needle bar, and a tapered substantially vertical thread guiding surface formed on said support for guiding said loose end of thread onto said surface of said support.

2. In a sewing machine of the type having a work support table, an upper needle bar and a lower needle bar adapted to pass a double pointed needle and a thread back and forth through work to be stitched, a thread receiving drum and a thread puller for pulling the loose end of said thread through said work and disposing it upon said drum; a combined thread support and lint trap having an opening formed therein through

which said lower needle bar may move, means mounting said support and trap above said drum and adjacent said lower needle bar, a tapered guiding surface formed on said support for guiding said loose end of thread into said support, and means for moving said thread upwardly along said guiding surface onto said support.

3. In a sewing machine of the type having a work support table, an upper needle bar and a lower needle bar adapted to pass a double pointed needle and a thread back and forth through work to be stitched, a thread receiving drum and a thread puller for pulling the loose end of said thread through said work and disposing it upon said drum; a thread support, a lint trap, means mounting said support and trap above said drum and adjacent said lower needle bar, a tapered guiding surface formed on said support for guiding said loose end of thread into said support, a thread trap located adjacent to and coacting with said thread support and lint trap, a reciprocatory thread engaging finger, and means for moving said finger into engagement with a portion of said thread to shift it laterally and dispose it in said thread trap and on said support.

4. In a sewing machine of the type having a work support table, an upper needle bar and a lower needle bar adapted to pass a double pointed needle and a thread back and forth through work to be stitched, a thread receiving drum and a thread puller for pulling the loose end of said thread through said work and disposing it upon said drum; a thread support, a lint trap, means mounting said support and lint trap above said drum and adjacent said lower needle bar, a thread guide formed on said support for guiding said loose end of thread into said support, a thread trap coacting with said thread guide and lint trap, said thread trap comprising substantially vertically spaced guide and thread positioning members mounted above said drum and adjacent said support and lint trap and positioned adjacent the path of movement of said thread puller, an oscillatory thread engaging finger, and means for moving said finger into engagement with a portion of said thread to shift it laterally to dispose said thread in said thread support and between said thread positioning members.

5. In a sewing machine of the type having a work support table, an upper needle bar and a lower needle bar adapted to pass a double pointed needle and a thread back and forth through work to be stitched, a thread receiving drum, and a thread puller for pulling the loose end of said thread through said work and disposing it upon said drum; a thread support, means mounting said support above said drum and adjacent said lower needle bar, a tapered guiding surface formed on said support, means for guiding said loose end of said thread onto said support, a thread trap mounted adjacent to and coacting with said thread support, a reciprocatory thread engaging finger, a thread hook on said finger, and means for moving said finger in timed relation with said movement of said needle bars to engage said hook with a portion of said loose end of said thread to displace it laterally along said guiding surface and dispose it in said thread trap and on said support.

6. In a sewing machine of the type having a work support table, an upper needle bar and a lower needle bar adapted to pass a double pointed needle and a thread back and forth through work to be stitched, a thread receiving drum, and a thread puller for pulling the loose end of said

thread through said work and disposing it upon said drum; a thread support, means mounting said support above said drum and adjacent said lower needle bar, a tapered guiding surface formed on said support for guiding said loose end of thread onto said support, a thread trap coacting with said guiding surface, said thread trap comprising spaced guide and thread positioning members positioned proximate said thread support and adjacent the path of movement of said thread puller, an oscillatory thread engaging finger, and means for moving said finger into engagement with a portion of said thread to shift it laterally to dispose said thread on said thread support and between said thread positioning members.

7. In a sewing machine of the type having a work support table, an upper needle bar and a lower needle bar adapted to pass a double pointed needle and a thread back and forth through work to be stitched, a thread receiving drum and a thread puller for pulling the loose end of said thread through said work and disposing it upon said drum, a thread support, means mounting said support above said drum and adjacent said lower needle bar, a thread guide formed on said support for guiding said loose end of thread into said support, a thread trap coacting with said thread guide, said thread trap comprising spaced guide and thread positioning members, means mounting said thread trap above said drum, adjacent said lower needle bar and adjacent the path of movement of said thread puller, an oscillatory thread engaging finger, and means for moving said finger into engagement with a portion of said thread to shift it laterally relative to said needle and to dispose said thread on said thread support and between said thread positioning members.

8. In a sewing machine of the type having a work support table, an upper needle bar and a lower needle bar adapted to pass a double pointed needle and a thread back and forth through work to be stitched, a thread receiving drum and a thread puller for pulling the loose end of said thread through said work and disposing it upon said drum, a thread trap, said trap including substantially vertically spaced thread guiding and trapping members, means mounting said trap above said drum and adjacent said lower needle bar, means for guiding said loose end of thread into said trap, a reciprocatory thread engaging finger, a thread hook on said finger, and means for moving said finger in timed relation with the movement of said needle bars and engaging said hook with a portion of said thread to shift it laterally along and between said members and dispose it in said thread trap.

9. In a sewing machine of the type having a work support table, an upper needle bar and a lower needle bar adapted to pass a double pointed needle and a thread back and forth through work to be stitched, a thread receiving drum and a thread puller for pulling the loose end of said thread through said work and disposing it upon said drum, a thread trap, means mounting said thread trap above said drum and adjacent said lower needle bars, said thread trap comprising substantially vertically positioned spaced upper and lower guide and thread positioning members positioned adjacent the path of movement of said thread puller, said upper member having a thread confining portion and a downwardly inclined portion having a guide nose on the free end thereof, said lower member having a substantially horizontal portion coacting with said

7
thread confining portion of said upper member and a terminal downwardly inclined portion substantially parallel with said downwardly inclined portion of said upper member and spaced therefrom; an oscillatory thread engaging finger, and means for moving said finger into engagement with a portion of said thread to shift it laterally to displace said thread along and between said thread guide and positioning members and locating it in said thread confining portion.

10. Thread handling mechanism for a sewing machine having a needle bar comprising a substantially horizontal thread support and lint trap, means mounting said support and trap adjacent said needle bar, a substantially vertical thread guiding surface formed on said support for guiding said thread upwardly onto said support, a thread trap coacting with said thread support and lint trap, means mounting said thread trap adjacent said thread support and lint trap, a thread engaging finger, and means for moving said finger in a closed path of travel into engagement with a portion of said thread to shift it along said guiding surface onto said support 20 and laterally to dispose it in said thread trap.

11. Thread handling mechanism for a sewing machine having a needle bar comprising a thread support, means mounting said support adjacent said lower needle bar, a thread guide formed on said support for guiding said thread into said support, a thread trap mounted adjacent and coacting with said thread guide, said thread trap comprising substantially vertically spaced guide and thread positioning members positioned at one side of said needle bar, an oscillatory thread engaging finger, and means for moving said finger into engagement with a portion of said thread to shift it laterally to move said thread along and over said thread guide and onto said support and along and between said thread positioning members into said trap.
